UNITED STATES PATENT OFFICE.

WILLIAM ISAAC RAVERT, OF HAZLETON, PENNSYLVANIA, ASSIGNOR TO STANDARD VENDING MACHINE COMPANY, OF HAZLETON, PENNSYLVANIA, A CORPORATION OF PENNSYLVANIA.

FRAUD-PREVENTIVE MEANS FOR COIN-CONTROLLED APPARATUS.

1,201,345.

Specification of Letters Patent.

Patented Oct. 17, 1916.

Application filed June 25, 1914. Serial No. 847,244.

To all whom it may concern:

Be it known that I, WILLIAM I. RAVERT, a citizen of the United States, residing at Hazleton, in the county of Luzerne and State of Pennsylvania, have invented a new and useful Fraud-Preventive Means for Coin-Controlled Apparatus, of which the following is a specification.

This invention has reference to improvements in fraud-preventive means for coin-controlled apparatus, and its object is to provide mechanism in the path of a coin traveling to the operating mechanism of a coin-controlled apparatus, which mechanism will direct a proper coin to the coin-controlled apparatus, but which will divert any other article, whether a coin or slug or other device, once introduced into the apparatus, so as to be returned to the person introducing it.

Since most check or coin-controlled apparatus are designed to be operated by a five cent piece, it will be considered that the proper coin for operating the apparatus is a five cent piece, although it is possible to use other coins with a properly designed apparatus, since a five cent piece and other coins have certain characteristics in common, although differing in other characteristics, which permit the adaptation of the invention to any coin.

A five cent piece is made of a nickel composition, and therefore the coin has a certain weight. The coin also has a certain rim thickness and a certain diameter and within the rim the two faces of the coin are depressed, the rim also being of a certain radial extent.

The great majority of devices used for the purpose of fraudulently operating coin-controlled machines lack one or more of the characteristics of a genuine coin, and as all of such characteristics must be substantially present in order to direct an introduced coin to the lock controlling mechanism of the vending machine, the fraud-preventive structure will refuse any slug or like device with which it may be attempted to operate the vending side of the machine.

Considering the course of a coin from the point of introduction until it has success-

fully passed the fraud-preventive devices, or, if not acceptable to the machine, has been returned to the user, the first thing in order is the entering aperture, and in the present instance this is so proportioned as to refuse to receive any coin of even a small fraction of an inch greater diameter than a proper coin. In accordance with the present invention the coin or other article if not too large is placed in an operating member of the machine which is to be manipulated by the user and is carried thereby into position to then travel to other parts of the device, but if a slug or similar article introduced through the usual coin receiving aperture or slot and be moved out of sight by the manipulating member be too thick it will simply return again into sight on the return of the manipulating member to its first position, and must be removed before the machine can operate at all. The first discarding device of the fraud-preventive structure, therefore, depends upon size, since an article of too great diameter cannot be introduced into the machine, and if too thick even to a slight degree will not travel farther into the machine, but will be returned to the person introducing it.

A coin or slug which is neither of too great diameter nor too thick passes on to the next testing mechanism, which relies for its action upon the presence of a laterally outstanding rim found on all genuine coins and some slugs sometimes used to fraudulently operate the vending machine. If such a rim be absent the article is at once discarded and returned to the user. Should the rim, however, be present, the coin or fraudulent slug, as the case may be, is directed into the proper course to be subjected to other testing structures, which in the present instance do or do not respond to the weight of the genuine or spurious device, as the case may be.

Since all genuine coins of the five cent type are made of a nickel composition, they have a different weight from a slug otherwise simulating the coin, but made of some other material. The weighing apparatus, therefore, is made very delicately responsive to a coin of proper weight, but will refuse to act under a coin of less than the

proper weight, even though the difference be but a very small fraction of the weight.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings, Figure 1 is an elevation of the fraud-preventive device with a portion of a casing assumed to be that of the vending machine shown in section. Fig. 1^a is a view of a portion of the structure of Fig. 1 omitted from the left hand side thereof. Fig. 2 is an elevation of the structure of Fig. 1 as viewed from the left hand side, with some parts in section, on the line 2—2 of Fig. 1. Fig. 3 is a section on the line 3—3 of Fig. 1. Fig. 4 is a section on the line 4—4 of Fig. 1. Fig. 5 is a section on the line 5—5 of Fig. 2, but showing the parts in a different operative position. Fig. 6 is a fragmentary perspective view of a portion of the structure. Fig. 7 is an elevation of the structure of Fig. 1 omitting some parts and showing the face of the structure remote from that viewed in Fig. 1. Fig. 8 is a section on the line 8—8 of Fig. 1 with some parts otherwise cut by the section shown in elevation. Fig. 9 is a fragmentary section on the line 9—9 of Fig. 4.

In the drawings there is shown a casing 1 which may if needed be made of an appropriate number of parts suitably assembled to permit manufacture and the introduction of certain parts into the casing.

Considering the structure as in the position it assumes when properly installed, the upper part of the casing is provided with an elongated passageway 2 substantially horizontal and of a depth from front to rear sufficient to receive a plate-like slide 3 having an arm 4 extending in the same direction as the length of the passageway 2 and terminating in a manipulating head 5 which in the particular structure shown is similar in shape to a spear head, this forming a convenient means for the application of the fingers of the human hand for moving the slide 3 lengthwise of the passageway 2, while the latter has at the end through which the arm 4 and head 5 project a lower ledge continuation 6 for a purpose which will presently appear.

The casing or body member 1 of the structure is formed with a bracket continuation 7 at the end remote from the ledge 6 and extending lengthwise along the bracket 7 is a

slot 8 continued for an appropriate distance into the corresponding wall bordering the passageway 2.

Formed in both upright walls of the passageway 2 are upright slots 9, 9^a, respectively, the slot 9 being close to the inner termination of the slot 8.

The slide 3 is provided with a chamber or passage 10 opening at the lower edge of the slide, and at a higher point the walls of the slide are pierced by openings 11, 12, respectively, in alignment laterally of the slide, and both communicating directly with the passage 10.

The opening 11 is made circular and is for convenience placed on the right hand side of the slide as viewed from the end provided with the arm 4. The opening 11 is of a diameter to snugly yet freely receive a five cent piece, the machine being considered as adapted for such coin. The opening or aperture 12 is made of slightly less diameter so that a coin properly introducable through the opening 11 cannot be introduced through the opening 12. Such coin will be arrested by the walls of the passage 10 surrounding the opening 12 and directed into the passage 10 by gravity. The thickness of the passage 10 between its side walls is such as to snugly yet freely receive a coin of proper value, such as a five cent piece.

In the normal condition of the parts the two openings or apertures 11 and 12 are exposed beyond the corresponding end of the passageway 2, but the passage 10 is underridden by the ledge 6, so that a coin introduced into the passage 10 will drop upon the ledge 6 and there remain and on the movement of the slide 3 into the passageway 2 for a purpose which will hereinafter appear, the coin will move with the slide resting upon the bottom wall of the passageway 2.

That end of the slide 3 remote from the arm 4 is provided with another arm 13 normally within the passage 2 and slowly rising away from the slide 3 to which it is connected near the lower end of the latter. The edges of the arm 13 are parallel one to the other and the arm is of such length and inclination that it terminates just under a flange 14 on the upper edge of the bracket 7 and forming a continuation of the upper wall of the passageway 2. The arm 13 at its free end has a continuation 15 underriding the flange 14 and carrying a pin 16 projecting through the slot 8, and beyond what may be termed the rear face of the casing 1 having a grooved end 17 engaged by one end of a continuation 18 of a spring 19, the latter being made fast to the rear face of the casing 1 by a clip 20 or otherwise.

Extending through the slots 9 and 9^a in the front and rear walls of the passageway 2 is a head portion 21 of a flat bar 22 disposed on what may be termed the front face

of the casing 1 and capable of sliding up and down in front thereof, the bar being substantially upright. At the lower end the bar passes through and is guided by a bracket 23 projecting from an appropriate portion of the casing 1 and having a return portion 24 so that the bar 22 is partially embraced by the bracket 23, the bar having a limited movement toward and from the casing while always held and guided by the bracket 23.

The head end 21 of the bar 22 is formed with a slot 25 through which the arm 13 passes, so that when the slide 3 is reciprocated, the bar 22 is given a lengthwise movement because of the cam action of the inclined arm 13. Ordinarily the slide 13 is at the extreme limit of its movement toward the left as viewed in Fig. 1, and this may be termed the initial or inoperative position, while the upper end of the arm 13 then traverses the slot 25 and the bar 22 is at the uppermost limit of its movement through the slots 9 and 9^a.

At the lower end the bar 22 is formed near the outer edge with a longitudinally projecting finger 26 and a laterally projecting toe 27 on the other edge toward the casing 1, and the corresponding face of the casing adjacent to the point the toe 27 occupies when at the highest limit of travel of the bar is recessed, as indicated at 28, so that under circumstances to be hereinafter referred to the toe 27 may lodge in the recess 28 to thereby lock the bar 22 against longitudinal movement, and especially a lowering movement.

The interior of the casing below the passageway 2 is formed with a laterally diverted coin chute 29 having an upper end 30 adjacent to the slots 9 and 9^a, but to the left of them as viewed in Fig. 5. When the slide 3 is moved to the full extent of its travel in the active direction, this extent being determined by the engagement of the slide with the head 21, the coin passage 10 is then in coincidence with the opening 30 of the chute 29. This chute is laterally diverted toward the right as viewed in Fig. 5, but with a declination that terminates in a substantially vertical downward portion 31, at the lower end of which the respective front and rear walls of the casing are formed with laterally extended slots 32, 33 made somewhat longer than the width of the coin chute. Below the slots 32, 33 there is within the casing a laterally expanded chamber 34 slightly deeper from front to rear than the thickness of any coin or slug which may reach it, and this chamber continues downwardly into a discard passageway 35 and another passageway 36 separated by an upright wall 37 having a beveled upper edge 38 directed toward the discard passageway 35.

What may be termed the rear wall of the passage 36 is continued downwardly and to the right as viewed in Fig. 5 as shown at 39, while the front wall is cut away to form a recess 40. At the lower end of the continuation 39 there is provided a short chute 41 having an inclined top or cover portion 42, and a side opening 43 stopping short of the bottom of the chute to provide an arresting ledge 44 for a purpose which will pres- 75 ently appear.

The wall 37 forming the division wall between the passageways 35 and 36 is widened at its lower end to provide a ledge 45 on the side remote from the discard passageway 35.

The recess 40 is provided for the reception of a scale pan 46 having parallel side walls 47 which may be somewhat higher than the diameter of a coin of proper value, and the pan is provided with an inclined bottom portion 48 which when the pan is elevated to its highest point is in position to discharge upon the cover or ledge 42 of the passage 41, which ledge is inclined in the same direction as the bottom 48 and is arranged to deliver into one side of a discard trough 49 which in turn may be continued in the downward direction to any suitable point, and is shown in Fig. 1 as extending through 90 what may be considered the front of a casing 50 assumed to inclose the entire machine, the trough opening into a pan or receptacle 51 from which a discarded article may be readily removed, since it is freely 100 accessible from the exterior of the apparatus. In order that any coin or other article received upon the scale pan 46 and finding its way upon the ledge 42 and from thence may be positively directed into the discard 105 trough, the ledge 42 is flanked on the outer side by a deflector plate 52 of appropriate shape.

The scale pan 46 is pendently hung by trunnions 53 to a double scale beam 54, one part 110 being to the front of the casing 1 and the other to the rear thereof, and both mounted upon alined pivots 55. The trunnion 53 connecting the scale pan to the part of the scale beam to the rear of the casing 1 extends through an appropriately curved slot 56 in the extension 39. Those ends of the two-part scale beam remote from the pan are joined by a yoke 57 carrying a weight 58 held thereto by an elongated set screw 59 115 extending through both the weight and the yoke and held in any suitable adjusted position by a lock nut 60, the set screw not only serving to hold the weight in place, but providing a delicate counterpoise for the 120 scale beam by which it may be very accurately adjusted to respond to coins of suitable weight, the lock nut 60 serving to fix the adjustment against accidental displacement. 125

In order to maintain the scale pan 46 in proper position, an equalizing link 61 is pivotally connected at one end by a staple 62 to the bottom of the scale pan, and at the other end by a staple 63 to an appropriate fixed portion of the casing 1, the link 61 being arranged in parallelism with the scale beam and freely moving therewith and also having an intermediate bend indicated at 64 to carry it out of the path of any coins dropping through the discard chute section 35.

Should a coin or slug ultimately reach the scale pan 46, and all proper coins and slugs possessing certain characteristics do, certain structures to be described are provided for causing such coins and slugs to move into the scale pan without shock or jar thereto, so that there is no disturbing momentum to interfere with accurate weighing. All proper coins reaching the scale pan depress the latter against the resistance of the weight 58 until the pan is arrested by engagement with the ledge 44, when the inclination of the bottom portion 48 of the pan causes the coin to roll off by gravity into the chute 41, by which it is directed into another chute 65 conveying the coin to the coin-controlled apparatus which may be of any suitable type operable by a coin of proper characteristics. Such a coin-controlled apparatus does not in itself form any part of the present invention, nor is the present invention limited in its use to any particular type of coin-controlled apparatus, wherefore such apparatus is neither shown nor described in this application.

If the coin reaching the scale pan be of light weight, or be a spurious article having such characteristics as will pass the fraud preventing devices up to the weighing structures, such a spurious article will be found almost without exception to be of light weight as compared to a genuine coin of proper value. Such a spurious article will, therefore, fail to depress the scale pan and will simply roll along the inclined bottom thereof on to the inclined ledge 42 to be directed by the latter into the discard trough 49 and so delivered at the front of the machine to the operator.

The delicacy of the weighing apparatus is maintained by having it quite separate from the coin chute with the sides arranged to have no sensible retarding effect upon the coin or slug.

The walls of the passageway 36 are brought closer together where discharging into the scale pan 46 than are the walls of the scale pan, so that there is no chance of the coin catching upon the edges of the scale pan to interfere with the movement of the coin or slug into the scale pan.

The slot 33 is elongated at the ends on the rear face of the casing by channels 66 to re-

ceive a shaft 67 having bearings in brackets 68, 69, respectively, the bracket 68 being made fast to one edge of the casing and the bracket 69 at the opposite edge thereof, and both brackets projecting beyond the front face of the casing for a purpose to be described.

Near one end of the slot 33 the shaft 67 carries a relatively broad roller 70 and near the other end of the same slot the shaft 67 carries a relatively narrow roller 71, these rollers being spaced apart less than the diameter of a proper coin. Mounted to move into and out of the other slot 32 are rollers 72, 73, corresponding to the rollers 70 and 71 in width, spacing and position, the roller 72 being in coactive relation to the roller 70 and the roller 73 being in coactive relation to the roller 71. The rollers 72 and 73 are mounted or formed on a short shaft 74 having bearings in legs 75 of a yoke member 76, the yoke portion of the yoke member being quite wide and terminating at the edge remote from the legs 75 in ears 77 mounted to rock upon a pivot pin 78 carried by a bracket 79 fast to the corresponding face of the casing 1, this being the front face. The shaft 74 with its rollers 72 and 73 may, therefore, be rocked about the pin 78 as a pivot support, the rocking being toward and from the rollers 70 and 71, and the extent of rocking being sufficient to cause the rollers 72 and 73 to enter the coin chute to a sufficient extent to grip a coin or other article between the pairs of rollers. At the upper edge of the yoke 76 there is formed an outstanding eye 80 for a purpose to be described.

The brackets 68 and 69 outstand from the front of the casing 1 for an appropriate distance and journaled in these brackets is a rock shaft 81 extending from one bracket to the other, and for a short distance beyond the bracket 69 where the shaft is made fast in a hub 82 on one end of a rock arm 83 formed or provided at the other end with an arc-shaped rack bar 84 having the teeth directed toward the axis of rocking of the arm 83.

Mounted upon the end of the shaft 67 adjacent to the bracket 69 are pinions 85 and 86, the pinion 85 being in constant mesh with the rack 84. Between the two pinions there is loosely mounted upon the shaft 67 a ratchet wheel 87 carrying pawls 88 in position to engage the pinion 86 for one way rotation of the ratchet wheel, the pawls riding idly over the pinion 86 on the rotation of the pinion in the opposite direction. In operative relation to the ratchet wheel is an anchor escapement 89 having a pendulum continuation 90, the escapement being mounted for rocking movements upon a pin 91 carried by the bracket 69.

The rock arm 83 is urged constantly in

one direction by one end of a spring 92 which is coiled about the hub 82, and has its other end held by a stud 93 fast to the bracket 69, the tendency of the spring being to move the arm upwardly in the installed position of the structure against the part or stop 24.

The bar 22 is so arranged as to move in close relation to that face of the arm 83 remote from the bracket 69, and on the arm 83 there is pin 94 in position to engage the lower end of the bar 22 between the finger 26 and the toe 27. When the bar 22 is moved downwardly by an inward movement of the slide 3 the pin 94 is engaged by the bar 22 and the arm 83 is rocked against the tendency of the spring 92 and the shaft 67 is rotated by the engagement of the rack bar 84 with the pinion 85. This movement, however, is inactive to the anchor escapement mechanism, since such movement causes the pinion 86 to ride idly under the pawl 88.

The shaft 81 is provided with three arms 95, 96 and 97, each shown as provided with a hub portion mounted on the shaft and made fast thereto by a set screw 98. While this provides for the adjustment of the arms upon the shaft, such adjustment is not necessary, since the arms may be formed as fixtures upon the shaft.

The arm 95 terminates in an angle extremity 98^a movable into engagement with a stop finger 99 pivotally mounted upon a stud 100 carried by the casing 1, the finger 35 rocking freely on the stud and the end 98^a of the arm 95 being movable into and out of engagement with the finger near the pivoted end. This finger is arched to avoid engagement with other parts of the mechanism, and is appropriately bent to provide a free extremity 100^a entering the space designed for the reception of the scale pan 46 and normally occupied thereby, the finger being so situated that its free extremity moves 40 easily into and out of the interior of the raised scale pan through the upper end thereof, being guided by a recess 101 in the casing adjacent to the passage 38. The free extremity of the finger is beveled, as indicated at 102, for a purpose to be described. Under ordinary inactive conditions the finger 99 is raised by the engagement therewith of the end 98^a of the arm 95, so that the beveled extremity 102 of the finger is just within 45 in the guiding recess 101 in position to drop by gravity into the scale pan when released by the arm 95. A pin 103 in the path of the finger 99 limits its movement into the scale pan after released by the arm 95.

The arm 96 is a double arm having two opposed claws 104 and 105, each of which is movable into engagement with the eye 80, and these claws are arranged eccentrically to the axis of rocking of the arm 96, which 50 extends on both sides of the shaft 81, that

on the engagement of either claw with the eye 80 the yoke member 76, and with it the shaft 74, are rocked away from the shaft 67. The yoke member 76 is normally constrained toward the shaft 67 by a spring 106 fast at one end to the casing 1 and at the other end bearing against the shaft 74 which may be intermediately reduced, so that the spring will prevent any rocking of the yoke member in its bearings, and thus maintain the rollers 70—72, and 71—73 in proper relation. To provide a good bearing surface for the spring and to provide for any lengthwise rocking of the shaft 74 to permit accommodation of the rollers to the margin and intermediate portions of a rimmed coin or slug, the spring 106 has its free extremity split, as shown at 107, so as to engage the shaft at different points, the bearings of the shaft 74 being made sufficiently loose to admit of such rocking movement.

The arm 97 is designed to operate a coin arresting mechanism. This mechanism comprises a rock lever 108 shown in Figs. 1, 6 and 8. This lever is mounted on a pivot pin or screw 109 around which there is coiled a spring 110 with one end fast to the pivot pin and one end bearing against the lever to normally constrain it to one limit of its movement. The ends of the lever are bent into angular relation to the length of the lever to constitute angle pins 111 and 112. The lever is pivoted on the front face of the casing 1 and the fingers 111 and 112 extend through curved slots 113 and 114 extending through the casing 1 from front to rear. These slots are curved about the axis of the pivot pin 109 as a center. The slot 113 enters the end 31 of the chute 29 and the slot 114 enters the passage 34, so that the finger 111 may be moved into and out of the path of a coin traveling along the chute 29 into the end 31 thereof, and the end or finger 112 may be moved into the path of a coin traveling between the rollers 71 and 73. The result of this is that when the lever 108 is in its normal position of rest, the finger 111 is in the path of a coin approaching the rollers 70 to 73, and when it is rocked in the other direction the finger 111 is moved out of the path of such a coin and the finger 112 is moved into the path of such a coin, to again move out of the path of the coin when the lever 108 returns to its first position under the action of the spring 110.

That end of the lever 108 carrying the finger 112 is bent at an angle to the length of the lever, and this bent portion is shown at 115. On the straight portion of the same arm of the lever having the bent extension 115 is an outstanding wing 116, which, when the lever is in its normal position, is situated at an angle to an angle member 117 at the outer end of the arm 97. When the 120

arm is rocked by a corresponding rocking of the shaft 81 the extremity 117 is brought into engagement with the wing 116 then at an angle to the path of travel of the extremity 117, and this wing being to one side of the pivot of the lever causes the lever 108 to yield to the movement of the arm 97, thus rocking the lever against the action of the spring 110, the extremity 117 finally moving into parallelism with the outer face of the wing 116, and thereby locking the lever against return movement under the action of the spring 110. When the shaft 81 rocks back to its first position, the lever 108 is released after the shaft has accomplished a portion of its return movement, so that the lever 108 will again move to the first position under the action of the spring 110.

The casing 1 may be made in most part of 20 a single casting with only such portions removable as may be necessary for the introduction of some of the other parts, or the whole casing may be formed in a single casting if such be desired. Wherever necessary brackets 118 are provided whereby the structure is made fast to the casing 50 or other support, and these brackets may or may not be made in one piece with the casing, these being matters of manufacture and 25 convenience. The brackets 68 and 69 are shown as formed separately from the casing and attached thereto by means of other brackets 119, 120, but even these parts may, if convenient, be made in one piece with the 30 casing, these being also matters of manufacture and convenience.

The scale beam 54 may have its pivots 35 of the customary pointed screw type engaging studs 121 projecting from opposite sides 40 of the casing 1 at an appropriate point, and best shown in Figs. 2 and 3, it being also customary to provide lock nuts 122 for the pointed screws.

The shaft 81 may be conveniently mounted 45 by providing the hub 82 with a reduced portion 123 to be mounted in a corresponding journal opening in the bracket 69. The portion 123 has a radial pin 124 projecting therefrom and the bracket has a slot leading 50 from its outer end into the bearing for the reduced portion 123. This slot is of a width sufficient to permit the passage of the shaft, but not of the reduced hub portion 123. The other end of the shaft has a reduced 55 portion 126 adapted to journal in the bracket 168. The shaft is moved through the slot 125 until the portion 123 is coincident with its bearing in the bracket 69, and then by moving the shaft lengthwise so that the pin 60 124 will pass transversely through the slot the end 126 of the shaft is seated in its bearing in the bracket 68 and the reduced portion 123 seats in the bracket 69. Then on turning the shaft 81 into position to bring 65 the arms 95, 96 and 97 into operative rela-

tion to the parts controlled thereby, the pin 124 is moved away from the slot 125 so that the shaft 81 is locked against escape from its bearings and yet may rotate to a sufficient extent without interference.

The fraud-preventive device of the present invention will automatically refuse to direct either a genuine coin or a counterfeit coin, or a slug or any other article which does not substantially duplicate a practically unworn genuine coin of the proper denomination for which the vending side of the machine may be set.

To make a fraud preventive device effective it must be made to meet, so far as it is possible, all conditions which might permit the fraudulent operation of the vending side of the machine. Furthermore, in order to meet the various conditions which might permit the fraudulent operation of the machine, the preventive device must at least in some parts be delicately responsive, and consequently delicately constructed and adjusted, wherefore it is necessary to prevent the introduction into the machine of any article liable to clog or injure the machine, for certainty of operation is important. Entering slots at the intake mouths of coin chutes do not prevent the forceful introduction of certain articles which might clog the machine, or do not certainly avoid a fraudulent operation of the machine by long pieces of wire or the like. To avoid such a contingency the present invention protects the initial parts of the fraud-preventive device by the employment of a plunger receptive mechanism into which the coin or slug or the like is placed, and by which said coin or the like is moved to a point where it may find entrance into the coin chute, the latter being wholly protected by the plunger from access by anything but an article simulating a coin or slug.

The opening 11 may be of a diameter but one or two thousandths of an inch larger than the diameter of a genuine coin of proper denomination. This prevents the introduction of slugs or like articles of over size and limits the intended fraudulent operator to articles of the same diameter, or of less diameter than a genuine coin. Moreover, the front to rear depth of the passage 10 is made to closely approach within a very few thousandths of an inch to the rim thickness of a coin of proper denomination. If it be attempted to place in the slide a fraudulent article of either suitable diameter or of less diameter, but of somewhat greater thickness than a genuine coin, such an article may be deposited in the slide and may be moved into the passageway 2 when the slide is pushed thereinto, but the frictional engagement of such an article with the front and rear walls of the passage 10 will prevent the article from dropping into the

coin chute when the passage 10 is brought into coincidence therewith, and the result is that the fraudulent article is brought back into sight by the return movement of the 5 slide. The distance from the opening 11 to the bottom of the slide is less than the diameter of the opening 11, so that the returned fraudulent article is visible to the operator, thus apprising the operator that 10 the machine will not receive such an article, and if the article be left in the slide, a subsequent honest operator may readily remove the fraudulent article because of the presence of the opening 12 by means of 15 which the article may be readily grasped by the fingers and lifted out of the slide.

Suppose that it be attempted to operate the machine by means of a thin disk or slug of either suitable diameter or of smaller 20 diameter than the suitable diameter. Such a disk may be readily introduced into the slide, and on pushing the latter into the passageway 2 the disk will drop into the chute 29 and gravitate along the latter until it 25 reaches the rollers 70 to 73, the finger 111 having in the meantime been moved out of the path of such disk, but the disk being of large enough diameter is arrested by the finger 112 then below the rollers. On the return of the 30 parts to the normal position the disk, which is urged toward the discard chute 35 by the finger 112, may be grasped between the rollers if not too thin, and will be fed straight downwardly thereby, but if too thin to be 35 grasped by the rollers, will simply fall through them when released by the finger 112. The edge 38 being on that side of the mid-point between the rollers of each pair remote from the discard chute 35, engages the 40 disk to the corresponding side of its center, and thus directs it into the discard 35 from which the disk gravitates into the trough 49, and rolls down the trough into the receptacle 51, thus apprising the operator that the 45 machine has refused to receive the disk. If such disk be of sufficiently small diameter, it will not be stopped by the finger 112, but at once drop into the discard chute, and from thence into the trough 49. Suppose, however, 50 that the slug introduced into the machine be of the same diameter as a genuine coin and of the same thickness, but is smooth faced, that is, there be no rim present. Under such circumstances the slug will enter the 55 chute 29 on the movement of the slide 3 into coincidence therewith, and will enter between and be grasped by the rollers 70 to 73, and ultimately be arrested by the finger 112. On the return of the slide to its first position 60 the rollers are rotated in a direction to feed the disk downwardly, but the rollers simply feed the disk straight downward and the finger 112 tends to divert the disk into the discard chute 35, this being assisted by the 65 beveled upper end 38 of the division wall 37,

so that all smooth plane disks, even though of proper size and thickness, are discarded. It is very common to employ ordinary washers in the attempt to operate vending machines, but the ordinary washer even though 70 of proper diameter and thickness, and possibly of proper weight, is directed, because of its plane faces, into the discard. However, such washers or slugs are usually of lighter weight than a genuine coin, and should such 75 a washer or slug because of the possible presence of a bur about its edge formed in the stamping of the slug be diverted into the passage 36, it will still be discarded because of its under weight, as will presently appear. 80

There are in existence large numbers of tokens quite similar to an ordinary five cent piece, and employed in some sections of the United States for trade purposes. Such tokens have marginal rims and sunken faces 85 and are often of the same diameter and thickness at the rim as a genuine five cent coin. Should such a token be introduced into the machine even with honest intent, it will still be refused, because such tokens, although 90 simulating in all other respects a genuine coin for which the machine may be set, are almost invariably of lighter weight. If it be assumed that such a token is introduced into the machine, it will find its way into the 95 chute 29 in the same manner as a genuine coin, and will reach and be engaged by the rollers 70 to 73, which are normally sufficiently separated to permit the coin or token to drop between them until arrested by the 100 finger 112 then in its path, for in this position of the parts the rollers have been separated by the movement of the claw 104 of the arm 96 into the eye 80, thus rocking the yoke 76 in a direction to move the rollers 72 and 105 73 out of the path of the coin.

The parts are so timed in operation that the claw 104 is moved out of the eye 80, thereby releasing the rollers 72 and 73 to move under the action of the spring 106 into engagement with the token then resting upon the finger 112. As soon as this is accomplished the arm 97 releases the lever 108, having in the meantime held the latter inactive by the engagement of the end 117 with the wing 116. Since the lever 108 is then free to be rocked by the spring 110, the finger 112 is moved out of the path of the token held by the rollers engaging it, the rollers 70 and 72 being wide enough to remain in engagement 115 with the rim of the token, while the rollers 71 and 73 engage the depressed faces of the token inside of the rim, since these last-named rollers are narrow and are so spaced from the broader rollers as to thus engage 120 the token.

The narrow rollers 71 and 73 will not readily ride over the raised marginal rims on opposite sides of the token, but the wider rollers quickly pass along the rim, with the 125 130

result that the token is rocked upon the rollers 71 and 73 as an axis, and when relieved from the rollers 70 and 72 quickly swings so as to be on the side of the wall 37 toward the chute continuation 36, and when finally released by the rollers 71 and 73 the token gravitates into the chute continuation 36. The release of the token from the rollers 71 and 73 is accomplished by the entrance of 10 the claw 115 into the eye 80, thus pulling the roller 73 away from the roller 71 and out of engagement with the token. However, while these operations have taken place, the end 100^a of the finger 99 has entered the 15 scale pan 46, which at this time is in the elevated position, and in part coincident with the passage 36. The token on leaving the rollers 71 and 73 drops on to the ledge 45 against which it is held by the beveled end 20 102 of the finger 99, the token being partly on the ledge and partly in the scale pan. Now, as the parts move to the full initial position, the return movement having been retarded by the pendulum 90 and escape- 25 ment controlled thereby, so that the return movement is relatively quite slow, the end 98 of the arm 95 finally engages the finger 99 and raises it out of the path of the token, whereupon the latter being free to roll along 30 the inclined bottom of the scale pan fully enters the latter, but being of insufficient weight to overbalance the scale, simply rolls along the scale pan and out of the open end thereof on to the ledge 42 to be directed by 35 the guard 52 into the trough 49, and is directed to the outside of the machine for return to the operator, thus apprising the latter that the token employed is refused by the machine.

40 That portion of the casing corresponding to the chute 29 is provided with eight openings 127 along the course of the chute 29 to indicate the lodging of any obstructive matter, should such enter the machine.

45 As it is possible that the scale pan may stick in the lowered position, in which position the weighted end of the scale beam 54 would be in the path of the lower portion of the free end of the arm 83, a cam projection 128 is there provided to move the scale pan out of the way and to its normal position on the return of the arm 83 to its normal position.

50 Suppose that the operator introduces into 55 the machine a genuine coin of the proper denomination, and not worn smooth, or not so worn as to be of light weight, for even genuine coins worn smooth or of too light weight are returned to the operator in the 60 same manner as smooth slugs or washers, or light weight slugs otherwise simulating genuine coins. Such a coin finds its way into the chute 29 as before, and between the rollers, and is swung by the rollers 71 and 73 65 into position to move into the chute contin-

uation 36, and is finally arrested by the end 102 of the finger 99 and by the ledge 45 ready to move into the scale pan. Since the return movement of the parts to the normal position is relatively slow, the finger 99 is 70 moved out of the scale pan with a like slow movement, so that the coin rolls into the scale pan deliberately and without any shock or jar thereto. Before the end 102 of the finger 99 has moved out of the scale pan 75 sufficiently to wholly release the coin, the latter being of greater weight than the counterweight 58, causes the scale pan to drop, so that by the time the coin is wholly released by the finger 99 the upper end of the 80 ledge 42 is in the path of the coin, thus preventing its escape from the scale pan until the latter has dropped to the ledge 44, whereupon the coin rolls into the passage 41 and ultimately into the chute 65 by which it is 85 directed to the vending side of the apparatus.

Brass and steel from which most five cent and higher denomination slugs are made, are both lighter than either nickel or silver, 90 wherefore otherwise exact duplicates of the genuine coins would be of lighter weight than genuine coins so that the scale is the final test of the genuineness or spuriousness of the article employed to operate the machine, and the scale is susceptible of very accurate adjustment. To make a brass or steel slug as heavy as a genuine coin, but no larger in diameter or thickness, such slug must either be flat or have a rim of much 95 greater width than that of a genuine coin. Under such circumstances the slug if flat will be discarded, or if the rim be of the necessarily great radial extent, the rollers 71 and 73 will engage the rim itself instead of engaging the face of the slug inside of the rim, thus moving the slug directly into the discard chute the same as though it were smooth throughout whether or not it be of the same weight as a genuine coin. The coin or slug 100 reaching the scale pan moves thereupon slowly and is held there for an appreciable time, so that the scale may be adjusted in a manner to cause a very small difference in weight to make it respond to a genuine coin, 105 but direct a spurious article or a light weight coin into the discard chute.

Since all improper devices which may be introduced into the machine are returned to the operator, any one who through carelessness or ignorance introduces a more valuable coin into the machine, such, for instance, as a ten cent silver piece, will have it returned without the operation of the machine, so that no loss is experienced 115 through such carelessness. Should by any means a second coin be introduced into the machine before the first coin has moved out of the way by the rollers propelling it, the finger 111 which in the normal position of 120 125 130

the parts is within the end 31 of the chute 29, will act as an arresting means for such second coin. Should the attempt be made to push in the slide a second time before 5 the parts have returned to their normal position, since the slide moves outwardly much more quickly than the parts first actuated thereby return to their normal position, a second actuation of the slide is prevented by 10 the engagement of the toe 27 in the recess 28 because of the manner in which the bar 22 is hung, causing the toe to swing into such position. It is only when the arm 83 has returned to its full upward position that 15 the arm 22 being engaged by the pin 94, is swung so that the toe 27 is outside of the recess 28, thereby unlocking the slide 3.

What is claimed is:—

1. In check controlled apparatus, a fraud 20 preventive structure comprising a diameter and thickness testing means, selecting means for rimmed checks or coins of predetermined character, and weight responsive testing means, all arranged in the order named, and 25 means associated with the weight responsive means for retarding the movements of the article to be tested on to said weight responsive means.

2. In check controlled apparatus, a fraud 30 preventive structure having a chute and comprising means for covering the entrance of the chute, said covering means being provided with a diameter and thickness testing means, means for selecting rimmed coins or 35 checks of predetermined characteristics, and weight responsive testing means for the coins or checks delivered to it, all the parts being arranged in the order named.

3. In check controlled apparatus, a fraud 40 preventive structure comprising a movable carrier for receiving checks, slugs or coins and having means for preventing access to the structure of devices over a predetermined diameter and thickness, selecting 45 means for choosing devices of predetermined surface character and discarding others, and weighing means for discarding all selected devices directed thereto of less than a predetermined weight, all of said means 50 being arranged in the order named with respect to the passage of an article through the fraud preventive structure, and operating means for the selecting means connected to the movable carrier for actuation thereby.

55 4. In check controlled apparatus, a fraud preventive structure comprising a movable carrier for receiving checks, slugs or coins and having means for preventing access to the structure of devices over a predetermined diameter and thickness, selecting 60 means for choosing devices of predetermined surface character and discarding others, and weighing means for discarding all selected devices directed thereto of less than 65 a predetermined weight, all of said means

being arranged in the order named with respect to the passage of an article through the fraud preventive structure, and operating means for the selecting means connected to the movable carrier for actuation thereby, 70 said operating means including means for storing power when moved by the carrier, and having means for retarding its movement under the action of the stored power.

5. In a check controlled apparatus, a body 75 member having a coin chute therein and a passageway in which the coin chute opens at its entering end, said body member having the passage therethrough transversely of the receiving end of the coin chute, a 80 slide mounted in said passage for movement to and fro therein and provided with a receptacle for a coin, check or slug with an entrance portion of predetermined size, the receptacle being of predetermined thickness, 85 and said slide being movable in the passageway to bring the receptacle into coincidence with the receiving end of the coin chute, means in the coin chute for engaging a coin or slug and diverting it in one direction or 90 another in accordance with the presence or absence of a rim on the coin or slug, and weighing apparatus for selectively determining by weight the retention or discarding of a coin or slug directed thereto by the 95 diverting means.

6. In a check-controlled apparatus, a fraud-preventive structure having an interiorly located coin chute, a slide at all times 100 protecting the coin chute from access from the exterior of the apparatus and provided with an interior chamber movable into and out of communication with the coin chute, said slide having a round entering opening to said chamber, through one side wall 105 thereof and constituting the sole means of communication with the chamber for introducing a coin thereinto, and means imparting to the slide a normal constraint to move to a position to expose the coin receiving 110 opening to access.

7. In a check controlled apparatus, a fraud-preventive structure having an interiorly located coin chute, a slide at all times 115 protecting the coin chute from access from the exterior of the apparatus and having an interior chamber movable into and out of communication with the coin chute, said slide having an opening through one side wall entering the chamber and constituting 120 the sole means for introducing a coin into the chamber, and said opening being of a size less than that of the chamber and of circular contour of a diameter substantially that of a coin to which the check-controlled 125 apparatus is responsive, and means for imparting to the slide a normal constraint to move to a position to expose the coin opening to access.

8. In a check controlled apparatus, a 130

fraud preventive structure having an interiorly located coin chute, and a slide provided with a receptacle movable into and out of coincidence with the coin chute and 5 at all times protecting the coin chute from access from the exterior of the apparatus, said slide having an entering opening to the receptacle at one side and provided with means imparting to it a normal constraint

10 to move to a position to expose the entering opening to access, said opening being of circular contour and of a diameter substantially that of a coin to which the check controlled apparatus is responsive, and said 15 receptacle being of a thickness to frictionally retain articles of a size to enter the receptacle but of greater thickness than a coin for which the vending apparatus is set.

9. In a check controlled apparatus, a 20 body member having a concealed coin chute, a slide having a receptacle therein and movable to carry the receptacle into coincidence with the coin chute, the slide being normally in a position with the receptacle exterior 25 to the body member, said slide being provided with a through passage opening from opposite sides of the slide into the receptacle, one end of the passage being of circular contour and of a size to receive a 30 coin or other article of proper diameter, and the other end of the passage being of circular contour and of smaller diameter and the receptacle being of a height to expose to view through the passage any article 35 lodged in the receptacle and of a diameter approximating that of the entering end of the passage leading into the receptacle.

10. In a check controlled apparatus, a 40 fraud preventive structure having an interior coin chute with a passageway extending transversely of the coin chute and communicating therewith, said passage having a ledge extension at one end, and a slide provided with a receptacle open at one end 45 to be brought by a movement of the slide into coincidence with the receiving end of the coin chute and when the slide is in normal position being spaced from the coin chute and in coincidence with the ledge at 50 one end of the passageway, said slide being provided with an opening of circular contour entering the receptacle at one side and of a size to admit a coin of the proper diameter and prevent admission of articles 55 of sensibly greater diameter.

11. In a check controlled apparatus, a 60 fraud preventive structure having an interior coin chute with a passageway extending transversely of the coin chute and communicating therewith, said passageway having a ledge extension at one end, and a slide provided with a receptacle open at one end to be brought by a movement of the slide into coincidence with the receiving 65 end of the coin chute and when the slide

is in normal position being at one end of the passageway, said slide being provided with an opening of circular contour entering the receptacle at one side and of a size to admit a coin of the proper diameter and prevent admission of articles of sensibly greater diameter, said slide being provided with a manipulating member at all times accessible to an operator.

12. In a check controlled apparatus, a 75 fraud preventive structure having an interior coin chute with a passageway extending transversely of the coin chute and communicating therewith, said passageway having a ledge extension at one end, and a slide provided with a receptacle open at one end to be brought by a movement of the slide into coincidence with the receiving end of the coin chute and when the slide is in normal position being spaced 80 from the coin chute and in coincidence with the ledge at one end of the passageway, said slide being provided with an opening of circular contour entering the receptacle at one side and of a size to admit a coin of the 85 proper diameter and prevent admission of articles of sensibly greater diameter, said slide being provided with a manipulating member at all times accessible to an operator, and comprising an arm projecting 90 from the slide in the direction of the length of the passageway in which the slide is movable and terminating in a head contracting toward the outer extremity for the application of the fingers of an operator.

13. In a check controlled apparatus, a 95 fraud preventive structure having a concealed coin chute and a slide with a receptacle therein movable into and out of coincidence with the receiving end of the coin 100 chute and at one limit of its travel in accessible position exterior to the structure, said slide having aligned circular openings at opposite sides each leading into the receptacle and one opening being larger than the other, the larger opening serving as an entering opening for coins or other articles of suitable size, and the smaller opening providing finger entering means in conjunction with the larger opening to permit grasping 115 an article lodged in the receptacle.

14. In a check controlled apparatus, means for introducing a coin thereto comprising a slide having a range of movement from a position of access to the interior of the apparatus, a cam arm carried by the slide, a reciprocating member engaged by the arm and movable in a direction substantially perpendicular to the movement of the slide by said arm, means for selectively directing a 125 coin or slug in the proper direction, or in the direction of discard in accordance with the character of the coin or slug, operating means for the selecting means, and connections between the member operated by the 130

slide and the operating means for the selecting means for causing the actuation of the last-named operating means.

15. In a check controlled apparatus, a reciprocal operating member, and selecting means for directing a coin or slug into a proper channel or into a discard in accordance with the character of the coin or slug, said selecting means comprising rotatable

10 members, actuating means for the rotatable members, and a reciprocal connection between the reciprocal operating member and the actuating means for the rotatable members, said connecting means being posi-

15 tively movable in both directions by the operating member and active to the actuating means for the rotatable members in one direction only, and said actuating means for the rotatable members being provided with

20 retarding means and with power storing means for causing the return movement thereof after the initial movement.

16. In a check controlled apparatus, a fraud preventive structure having an accessible reciprocal member, another member movable by the reciprocal member in a direction transverse to the movement of said reciprocal member, a rotatable means for selectively acting upon coins or

30 slugs directed thereto, and operating means for the rotatable members including power storing means, the second-named member controlled by the first-named member being in coactive relation to the operating means

35 for the rotatable members for moving said operating means in one direction to store power therein, and inactive thereto on the return movement, and said operating means for the rotatable members being provided

40 with retarding means for restricting its speed of movement under the action of the stored power.

17. In a check controlled apparatus, a fraud preventive device having coin selecting and propelling means, actuating means therefor including power storing means, means accessible from the exterior of the machine for storing power in the actuating means, and retarding means associated with

50 the actuating means for causing a relatively slow return movement of the actuating means under the stored power.

18. In a check controlled vending machine, a fraud preventing structure having coin selecting and propelling means shaped and spaced to engage a coin both at the rim and interior thereto, and acting directly on the coin for selectively directing a proper coin edgewise toward the operating mechanism of the machine, and means for retarding the active movement of said coin selecting and propelling means.

19. In a check controlling vending machine, a fraud preventive structure having adjacent rotatable coin engaging and propelling members spaced apart and movable one toward and from the other and each having coin engaging and propelling parts separated by a distance less than the diametric width of a proper coin interior to its

70 rim portions, operating means for causing the rotation of the rotatable members and including power storing means, means for actuating the operating means in a direction to store power for subsequently driving the operating means, and retarding means for the operating means during its movement under the stored power.

20. In a check controlled apparatus, a fraud preventive structure having rotatable coin engaging and propelling means, a rack and connections therefrom to the coin engaging and propelling means, said rack having power storing means associated therewith for moving it in one direction, a one-way actuating means for the rack for moving it in opposition to the power storing means to store power therein, and a pendulum escapement connected to the coin propelling means and having a one way connection thereto for the actuation of the pendulum escapement on the movement of the rack under the action of the power storing means.

21. In a check controlled apparatus, a fraud preventive structure comprising pairs of coin engaging and propelling rollers with the rollers of each pair separated by a distance less than the diametric width of a proper coin, one pair of rollers being movable toward and from the other pair of rollers, gear connections for rotating one pair of rollers and including a rack, and power storing means tending to move the rack in one direction, means movable with the rack for moving the other pair of rollers away from the first-named pair of rollers, means for moving the rack in a direction opposed to the action of the power storing means to at the same time store power therein, and a pendulum escapement having a one way connection to the first-named pair of rollers to retard the rotation thereof under the action of the power storing means.

22. In a check controlled apparatus, two pairs of rotatable rollers with the rollers of each pair spaced apart a distance less than the diametric width of a proper coin and one pair of rollers being movable toward and from the other pair, whereby the rollers engage, propel and release a coin or slug passing between them, one pair of rollers being mounted upon a shaft, a pinion mounted upon said shaft, a rockable segmental rack engaging the pinion, a spring for moving the rack in one direction and storing power when the rack is moved in the other direction, means for moving the rack in a direction to store power in the spring, a shaft carrying the rack, a rock member car-

rying the other pair of rollers and provided with an eye portion and having a normal tendency toward the first-named pair of rollers, and a rock arm mounted on the second-named shaft and provided with opposed claws movable into and out of the eye to cause movements of the second pair of rollers away from the first-named pair.

23. In a check controlled apparatus, two pairs of rotatable rollers with the rollers of each pair spaced apart a distance less than the diametric width of a proper coin and one pair of rollers being movable toward and from the other pair, whereby the rollers engage, propel and release a coin or slug passing between them, one pair of rollers being mounted upon a shaft, a pinion mounted upon said shaft, a rockable segmental rack engaging the pinion, a spring for moving the rack in one direction and storing power when the rack is moved in the other direction, means for moving the rack in a direction to store power in the spring, a shaft carrying the rack, a rock member carrying the other pair of rollers and provided with an eye portion and having a normal tendency toward the first-named pair of rollers, and a rock arm mounted on the second-named shaft and provided with opposed claws movable into and out of the eye to cause movement of the second pair of rollers away from the first-named pair, the first-named shaft having an escapement wheel thereon with a one way connection to the shaft, and an escapement anchor and pendulum in operative relation to the escapement wheel for retarding movement of the rack and parts controlled thereby under the action of the power storing means.

24. In a check - controlled apparatus, a fraud preventive structure having coin engaging and propelling means, a device mounted for to and fro movement and connected to the coin engaging and propelling means, said device having power storing means associated therewith for moving it in a direction to actuate the coin engaging and propelling means, a coin receiving slide, and a connection between the coin receiving slide and said device comprising a bar movable by the slide and engaging said device in a direction to cause storing of power in the power storing means.

25. In a check controlled apparatus, a fraud preventive structure comprising coin engaging and propelling means, a rock arm provided with rack and pinion connections to the coin engaging and propelling means, power storing means active to the rock arm to move it in one direction, means for retarding movement of the rock arm under the action of the power storing means, a coin receiving slide movable in a direction transverse to the direction of movement of

the rock arm and provided with a cam portion, and a connection between the slide and the rock arm comprising a bar engaged and movable by the cam portion of the slide in the same direction as the rock arm and associated with the latter to impart a movement to the rock arm to cause the storing of power in the power storing means.

26. In a check controlled apparatus, a fraud preventive structure comprising coin engaging and propelling means, a rock arm provided with rack and pinion connections to the coin engaging and propelling means, power storing means active to the rock arm to move it in one direction, a coin receiving slide movable in a direction transverse to the direction of movement of the rock arm and provided with a cam portion, and a connection between the slide and the rock arm comprising a bar engaged and movable by the cam portion of the slide in the same direction as the rock arm and associated with the latter to impart a movement to the rock arm to cause the storing of power in the power storing means, said rock arm having retarding mechanism associated therewith and active to the rock arm on the movement thereof under the power storing means and the connecting bar between the slide and the rock arm having a one way connection thereto for the return of the slide to initial position without action of the rock arm.

27. In a check controlled apparatus, a fraud preventive structure comprising coin engaging and propelling means, a rock arm provided with rack and pinion connections to the coin engaging and propelling means, power storing means active to the rock arm to move it in one direction, a coin receiving slide movable in a direction transverse to the direction of movement of the rock arm and provided with a cam portion, and a connection between the slide and the rock arm comprising a bar engaged and movable by the cam portion of the slide in the same direction as the rock arm and associated with the latter to impart a movement to the rock arm to cause the storing of power in the power storing means, said rock arm having retarding mechanism associated therewith and active to the rock arm on the movement thereof under the power storing means and the connecting bar between the slide and the rock arm having a one way connection thereto for the return of the slide to initial position without action of the rock arm, and said connecting bar and a fixed portion of the structure having coacting parts for latching the bar and through it the slide against a second operation before the rock arm has reached the limit of its movement under the power storing means.

28. In a check controlled apparatus, a fraud preventive structure comprising coin engaging mechanism, a rockable member for

actuating the coin engaging mechanism, power storing means for causing movement of the rockable member in one direction, retarding means for slowing up movement of the rockable member under the power storing means; a reciprocable coin receiving slide having power storing means for returning it to initial position after actuation, and a connecting member between the slide and the rockable member comprising a bar movable by the slide in the same direction as the rockable member, separable connections between the bar and the rockable member for permitting return movements of the bar without engaging the rockable member, coacting latch means between the bar and the fixed portion of the structure, and coacting connections between the bar and the rockable member for causing the unlatching of the bar on the attainment of the rockable member to the limit of its movement under the power storing means.

29. In a check controlled apparatus, fraud preventive means comprising coin engaging and controlling devices, a rockable member for actuating the coin controlling and engaging devices, power storing means for moving the rockable member in one direction, retarding means for slowing up the movement of the rockable member under the power storing means, a reciprocable coin receiving slide having a cam arm and provided with power storing means for the return of the slide to initial position after actuation, a bar engaged and movable by the cam arm and at the end remote from the cam arm having projecting portions in the direction of the length and laterally of the bar, a supporting structure for the named parts having a recess for the lateral projection on the bar, and a rockable member provided with a projecting portion for engaging the bar and the longitudinal projection therefrom.

45 30. In a check controlled apparatus, a fraud preventive structure provided with a coin chute, coin engaging members projecting into the coin chute, a rock lever having fingers at opposite ends projecting into the coin chute on opposite sides of the coin engaging means therein, said lever being provided with a spring for constraining it to one limit of its movement, and also having an angle wing thereon, and a rock arm in position to engage the wing to rock the lever, and to then move against the face of the wing to lock the lever in the actuated position.

31. In a check controlled apparatus, a fraud preventive structure provided with a weighing mechanism, and positively acting stop means for temporarily holding a coin or the like from engagement with the weighing mechanism after reaching a point for entrance thereto, said stop means having

means for moving it into and out of the path of the coin, whereby shocks or jars to the weighing mechanism because of momentum of a coin or the like is prevented.

32. In a check controlled apparatus, a fraud preventive structure having weighing means provided with a scale pan and a coin chute leading thereto, a coin engaging device for arresting the travel of the coin at the entrance of the scale pan, and means for moving the arresting device out of the path of the coin or the like and timed to have such movement only after the coin or the like has been brought substantially to a stop at the entrance of the scale pan.

33. In a check-controlled apparatus, a fraud preventive structure provided with weighing means including a scale beam and a scale pan, the latter having means associated therewith for causing it to move in a substantially straight up and down path and said scale pan also having upstanding sides spaced apart to receive and hold a coin on edge only and provided with a coin sustaining bottom portion continually inclined with the end of the pan at the high end of the bottom constituting the receiving end of the pan and that end of the pan at the low end of the bottom constituting the delivery end of the pan.

34. In a check controlled apparatus, a fraud preventive structure provided with weighing means including a scale beam and a scale pan, the latter being shaped to receive the coin on edge only and having a coin sustaining portion continually inclined to cause a coin received therein to gravitate therefrom, said scale pan having associated therewith a coin arresting device movable into and out of the scale pan and timed in movement to cause the coin or the like reaching the scale pan to enter the latter slowly, whereby shocks and jars are avoided.

35. In a check controlled apparatus, a fraud preventive structure provided with weighing apparatus including a scale pan movable by a coin of proper weight and having a bottom slanting downwardly from one end constituting the receiving end to the other end constituting the discharge end and closely approaching sides spaced to freely receive a coin on edge and so hold it until discharged from the scale pan, and means associated with the scale pan for causing it to move up and down in a substantially straight line.

36. In a check controlled apparatus, a fraud preventive structure provided with weighing apparatus including a scale pan movable by a coin of proper weight and having an inclined bottom and closely approaching sides spaced to freely receive a coin on edge and so hold it until discharged from the scale pan, said scale pan having associated therewith a coin arresting finger

movable into and out of the scale pan when in position to receive a coin for causing the coin or the like to enter the scale pan slowly, whereby shocks and jars to the weighing apparatus due to momentum of the coin are avoided.

37. In check controlled apparatus, a fraud preventive structure including means for testing coins and other like articles as to diameter, thickness and the presence or the absence of a rim, and a weighing device in the path of a coin or the like successfully passing the other testing means, said weighing apparatus including a scale pan with an inclined bottom portion and with closely approaching sides for holding the coin or the like on edge, and a finger movable into and out of the scale pan while in the elevated position to arrest the coin entering the scale pan before engaging the bottom thereof, said finger having actuating means for imparting to it a relatively slow movement in a direction to release the coin to roll with like slowness on to the scale pan, whereby the scale pan is given time to respond to a coin of proper weight.

38. In check controlled apparatus, a fraud preventive structure including means for testing coins and other like articles as to diameter, thickness and the presence or the absence of a rim, and a weighing device in the path of a coin or the like successfully passing the other testing means, said weighing apparatus including a scale pan with an inclined bottom portion and with closely approaching sides for holding the coin or the like on edge, and a finger movable into

and out of the scale pan while in the elevated position to arrest the coin entering the scale pan before engaging the bottom thereof, said finger having actuating means for imparting to it a relatively slow movement in a direction to release the coin to roll with like slowness on to the scale pan, whereby the scale pan is given time to respond to a coin of proper weight, said scale pan having also associated therewith means for diverting a coin or the like of less than the proper weight away from the vending side of the apparatus while the scale pan remains in its initial position.

39. In check controlled apparatus, a fraud preventive structure including a series of means for testing coins or slugs applied to the machine for the operation thereof, with weight testing means at the end of the series, said weight testing means having associated therewith means for arresting movement of a coin or the like reaching such weight testing means before entrance thereto, said arresting means having means for moving it out of the path of the coin or the like reaching the weighing means to permit the coin or the like to enter upon the weight testing means without shocks or jars due to momentum of the coin or the like.

In testimony that I claim the foregoing as my own I have hereto affixed my signature in the presence of two witnesses.

WILLIAM ISAAC RAVERT.
